CLAIM

The ornamental design for the stackable and nestable shelves
with reinforced platform, as shown and described.

DESCRIPTION

FIG. 1 is an isometric view of the flat wire stackable and
nestable shelfe with reinforced platform of this invention;

FIG. 2 is a side view, the opposite side view being a mirror
image thereof;

FIG. 3 is an end view, that opposite end view being a mirror
image thereof;

FIG. 4 is a bottom view; and,

FIG. 5 is top view.
